UNITED STATES PATENT OFFICE.

CLARENCE E. OSBORNE, OF PORTLAND, OREGON.

AUTOMATIC AIR-VALVE FOR CARBURETERS.

1,379,474.

Specification of Letters Patent.

Patented May 24, 1921.

Application filed April 13, 1920. Serial No. 373,511.

To all whom it may concern:

Be it known that I, CLARENCE E. OSBORNE, a citizen of the United States, residing at Portland, in the county of Multnomah and State of Oregon, have invented certain new and useful Improvements in Automatic Air-Valves for Carbureters; and I do hereby declare the following to be a full, clear, and exact description of the invention, such as will enable others skilled in the art to which it appertains to make and use the same.

This invention relates to an automatic air valve for a carbureter and the principal object is to provide means for controlling the air supply to the carbureter in accordance with requirements of the engine.

A further object is to provide means for reducing the consumption of the fuel to a minimum.

20 A still further object is to provide a valve and a casing therefor which may be applied to the air intake of the carbureter, and which shall admit a quantity of air sufficient to permit of securing the best results with a given amount of fuel the degree of opening of the valve depending upon the degree of suction resulting from the operation of the engine.

25 A still further object is to provide a valve and a casing therefor which can be manufactured and sold as a separate attachment, complete in itself, and which can be applied in the position indicated without the necessity of employing expert assistance, and 35 without the use of particular tools or of attaching devices.

With the foregoing and other objects in view, the invention consists in the novel construction, combination, and arrangement of 40 elements hereinafter described and claimed.

In the accompanying drawings the figure is a view in side elevation and section, showing the device as applied to the carbureter, at the intake side thereof, a portion of the 45 engine and the intake manifold being illustrated.

It is well understood that an internal combustion engine gives the best results from a given amount of fuel when the proportion 50 of air admitted can be accurately controlled, and especially when this control can be effected automatically. In the present device the air intake of the carbureter is designated 10, the carbureter is shown at 12, and 55 the intake manifold for the engine is designated 14.

The attachment claimed herein may be manufactured as an independent article and readily applied by anyone. It consists of a casing 15 providing a valve seat 16 for a ball valve 17. This valve is normally retained in a closed position by means of a spring 18 extending centrally and longitudinally of the valve casing and connected with a transverse element 19. This element 25 last named may conveniently be made by slitting the end of the casing circumferentially, as shown at 20, and forcing inwardly the strip of metal thus separated, the ends of the strip of course maintaining their 30 connection with the walls of the casing.

As the supply of fuel increases with the speed of the engine, so also the supply of air increases, the greater suction causing the valve 17 to open farther, with the result indicated. It is not only possible to save a considerable percentage of the fuel, but the deposit of carbon in the cylinders is also 35 greatly reduced.

What is claimed is:—

1. An attachment for carbureters comprising a tubular valve casing, cylindrical in configuration, a valve seat connected with the walls of the casing, a ball valve coöperating with the seat, a spring connected with the valve, one end of the casing being slit circumferentially and the strip formed thereby being deflected inwardly to form a transverse element extending across the valve casing, said spring being connected with the transverse element. 80

2. An attachment for carbureters comprising a valve casing having one end turned outwardly and its opposite end curved inwardly and apertured to form a valve seat, 95 a ball valve coöperating with said seat, a spring connected with said valve, the first mentioned end of the casing being split circumferentially and the strip formed thereby being deflected inwardly to the longitudinal center of said casing to form a transverse element extending partially across the valve casing, said spring being connected with said transverse element to resiliently retain said valve in engagement with 100 said valve seat.

In testimony whereof I affix my signature in presence of two witnesses.

CLARENCE E. OSBORNE.
